STAND FOR FISHING RODS OR SIMILAR ELONGATED ARTICLES

Richard Emanatian, Cohoes, N. Y.

Application March 26, 1954, Serial No. 29,698

Term of patent 14 years

(Cl. D31—4)

To all whom it may concern:

Be it known that I, Richard Emanatian, a citizen of the United States residing at Cohoes, in the county of Albany and State of New York, have invented a new, original, and ornamental Design for Stand for Fishing Rods or Similar Elongated Articles, of which the following is a specification, reference being had to the accompanying drawing, forming part thereof.

Fig. 1 is a front elevational view of a stand for fishing rods or similar elongated articles, showing my new design;

Fig. 2 is a side elevational view thereof; and Figs. 3, 4 and 5 are sectional views on the lines 3—3, 4—4 and 5—5, respectively of Fig. 1.

I claim:

The ornamental design for a stand for fishing rods or similar elongated articles, as shown.
